PLASTIC JUG

Norman A. Kelly, Wayne Township, Kosciusko County,
Ind., assignor to Crystal Preforming and Packaging,
Inc., Warsaw, Ind., a corporation of Indiana

Filed Nov. 12, 1965, Ser. No. 88,066

Term of patent 14 years

(Cl. D58—5)

Fig. 3

FIGURE 1 is a perspective view of a plastic jug embodying my new design wherein the finish and closure thereof are of the screw type as shown;

FIGURE 7 is a perspective view of a plastic jug showing another embodiment of my design, wherein the finish and cap thereof are of the slip type as shown; and

I claim:

The ornamental design for a plastic jug, as shown and described.
